CLAIM

The ornamental design for a planter pot drain tray, as shown and described.

DESCRIPTION

FIG. 1 is a top view of a planter pot drain tray according to a first embodiment;
FIG. 2 is a bottom view of the planter pot drain tray of FIG. 1;
FIG. 3 is a first side view of the planter pot drain tray of FIG. 1;
FIG. 4 is a second side view of the planter pot drain tray of FIG. 1;
FIG. 5 is a third side view of the planter pot drain tray of FIG. 1;
FIG. 6 is a fourth side view of the planter pot drain tray of FIG. 1;
FIG. 7 is a first perspective view looking toward a top of the planter pot drain tray of FIG. 1;
FIG. 8 is a second perspective view looking toward the top of the planter pot drain tray of FIG. 1;
FIG. 9 is a third perspective view looking toward a bottom of the planter pot drain tray of FIG. 1;
FIG. 10 is a fourth perspective view looking toward the bottom of the planter pot drain tray of FIG. 1;
FIG. 11 is a top view of a planter pot drain tray according to a second embodiment;
FIG. 12 is a bottom view of the planter pot drain tray of FIG. 11;
FIG. 13 is a first side view of the planter pot drain tray of FIG. 11;
FIG. 14 is a second side view of the planter pot drain tray of FIG. 11;
FIG. 15 is a third side view of the planter pot drain tray of FIG. 11;
FIG. 16 is a fourth side view of the planter pot drain tray of FIG. 11;
FIG. 17 is a first perspective view looking toward a top of the planter pot drain tray of FIG. 11;
FIG. 18 is a second perspective view looking toward the top of the planter pot drain tray of FIG. 11;
FIG. 19 is a third perspective view looking toward a bottom of the planter pot drain tray of FIG. 11; and,
FIG. 20 is a fourth perspective view looking toward the bottom of the planter pot drain tray of FIG. 11.
The broken lines illustrate portions of the planter pot drain tray and form no part of the claimed design.
